CLAIM

The ornamental design for the bird feeder as shown and described herein.

DESCRIPTION

FIG. 1 is a perspective view of a bird feeder showing the design;

FIG. 2 is the front elevation view thereof;

FIG. 3 the rear elevation view thereof;

FIG. 4 the left side elevation view thereof;

FIG. 5 is the top plan view thereof; and,

FIG. 6 is the bottom plan view thereof.

The right side elevation view is omitted because it is a mirror image of the left side.

The broken lines shown in the drawings represent portions of the bird feeder that form no part of the claimed design.
